UNITED STATES PATENT OFFICE.

HARRY A DOUGLAS, OF BRONSON, MICHIGAN, ASSIGNOR TO DOUGLAS & RUDD MFG. CO., OF BRONSON, MICHIGAN, A CORPORATION OF MICHIGAN.

CIRCUIT-CONNECTOR.

1,308,172.

Specification of Letters Patent.

Patented July 1, 1919.

Original application filed October 24, 1917, Serial No. 198,339. Divided and this application filed May 23, 1918. Serial No. 236,083.

To all whom it may concern:

Be it known that I, HARRY A. DOUGLAS, citizen of the United States, residing at Bronson, in the county of Branch and State 5 of Michigan, have invented a certain new and useful Improvement in Circuit-Connectors, of which the following is a full, clear, concise, and exact description.

My invention relates to tubular shells and 10 is of particular service where such shells are employed in the construction of circuit continuing or connecting devices in which contact carrier cores are used, though the invention is not to be limited to this use.

15 It is the object of my invention to provide an improved form of arm or lug projecting from the shell and a novel assembly of this arm with the shell. In carrying out my invention I provide an outer bulging portion 20 along and within which an arm extends. This bulging portion of the shell permits a contact carrying core that conforms in cross section to the bore of the shell to be placed within the shell in the same zone with the 25 arm that is received in the bulging portion of the shell, while allowing such arm to be confined between the contact carrying core and the metal of the shell. The shell also desirably carries a lug spaced apart from 30 the aforesaid bulging portion of the shell and which coöperates with the bulging portion of the shell, and preferably also the contact carrying core, to hold the arm and shell in assembly without the aid of a fastening 35 screw.

I will explain my invention more fully by reference to the accompanying drawing in which Figure 1 is a longitudinal sectional view of a shell; Fig. 2 is a longitudinal sectional view of the shell in assembly with the contact carrying core; Fig. 3 is a longitudinal sectional view of the shell shown in Fig. 2 on line 3—3 of Fig. 2; Fig. 4 is a cross section on line 4—4 of Fig. 3; and Fig. 5 is a 45 side elevation.

Like parts are indicated by similar characters of reference throughout the different figures.

The shell 1 has bayonet slots 3, 4, each of 50 the bayonet slots 4 being partially formed in the two opposite parallel and abutting edge portions of the sheet out of which the shell is formed as indicated at 4¹, the portions 4¹ matching, when the sheet is curled,

to form the bayonet slots 4. In these same 55 opposite edges mortises 5 and tenons 6 are formed, the mortises and tenons interengaging to maintain the shell in shape.

The contact carrier 8 constitutes a core 60 and carries contacts 9 adapted for engagement with contacts upon circuit continuing devices that are receivable in the ends of the shell and are adapted to be coupled therewith with the aid of the bayonet slots 3 and 4, as is well understood by those familiar 65 with the art. This contact carrying core, generally of insulating material, is preferably driven tightly into the shell further to effect and maintain tight engagement between the mortises and tenons 5 and 6. 70 Such core, however, may otherwise be assembled with the shell, if desired.

The core is cylindrical to correspond to the cylindrical bore of the shell. An intermediate portion of the core is outwardly 75 bulged as indicated at 10 to afford sufficient space between the core and the bulging part 10 of the shell for the reception of an arm 11 that has a continuation 12 extending through the shell. This continuation 12 is 80 preferably angular to the arm 11 to form therewith an angular lug of which the part 12 is also an arm. The arm 12 of the lug is shown as equipped with a screw hole 13 whereby the shell may be mounted. The 85 arm 12 of the angular lug is wider at the arm 11 so as to engage the sides of the lateral opening 14 in the shell that intervenes between the bulging portion 10 and an outwardly projecting lug 15 formed by a part 90 of the metal that is displaced in making the opening 14. The arms 11 and 12 both extend through the opening 14 that is at the bulging portion 10 to the exterior of the shell, the arm 12 extending sufficiently beyond the shell to form an attaching means. 95

In assembling the parts the arm 11 of the angular lug is inserted through the opening 14, the angular lug then being turned until the arm 12 of the angular lug rests against 100 the lug 15 and is at right angles to the shell. The contact carrying core is thereafter placed in the shell to be in the zone that includes the arm 11 of the angular lug, the core serving to hold the arm 11 of the angular lug in position against the inner surface of the bulging portion 10 whereby the angular lug and the shell are maintained in 105

assembly. As hitherto stated the core may be driven into position so as to be held in fixed relation with the shell or may be otherwise so held.

6. While I prefer to rely upon the core to hold the arm 11 of the angular lug against the bulging portion 10 of the shell, I do not wish to be limited to this characteristic.

10. The present application is a division of my original application Serial No. 198,339, filed October 24, 1917, features of novelty not herein claimed being claimed in the earlier application.

15. While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

20. 1. A shell having an outwardly bulging portion, a lateral opening at the bulging portion, and a projecting lug near said bulging portion; in combination with an angular lug having one arm received in said bulging portion and its other arm projecting through said opening and engaging the first aforesaid lug; and a core within the shell in the zone of the first aforesaid arm and engaging it to maintain the angular lug and shell in assembly.

25. 2. A shell having an outwardly bulging portion, a lateral opening at the bulging portion, and a projecting lug near said bulging portion; in combination with an arm received in said bulging portion and projecting

through said opening and engaging said lug; and a core within the shell in the zone of 40 said arm to maintain the arm and shell in assembly.

3. A shell having an outwardly bulging portion and a lateral opening; in combination with an angular lug having one arm received in said bulging portion and its other arm projecting through said opening; and a core within the shell in the zone of the first aforesaid arm and engaging it to maintain the angular lug and shell in assembly. 50

4. A shell having an outwardly bulging portion and a lateral opening; in combination with an arm received in said bulging portion and projecting through said opening; and a core within the shell in the zone 55 of said arm and engaging the same to maintain it and shell in assembly.

5. A shell having an outwardly bulging portion, a lateral opening at the bulging portion, and a projecting lug near said 60 bulging portion; in combination with an angular lug having one arm received in said bulging portion and its other arm projecting through said opening and engaging the first aforesaid lug.

6. A shell having an outwardly bulging portion, a lateral opening at the bulging portion, and a projecting lug near said 65 bulging portion; in combination with an arm received in said bulging portion and projecting through said opening and engaging said lug.

In witness whereof, I hereunto subscribe my name this 8th day of May, A. D. 1918.

HARRY A. DOUGLAS.
